TRIGGER MOTOR

Richard C. Coupland, United States Army,
Norfolk, Va.

Application October 2, 1934, Serial No. 746,531

8 Claims. (Cl. 89—27)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a trigger motor such as is used in connection with a synchronized control system for guns which will permit the guns to be fired between the blades of a rotating propeller of aircraft.

10 The purpose of the invention is to provide a compact trigger motor of light weight, which may be readily adjusted and which will be positive and reliable in operating.

To these and other ends, the invention consists 15 in the construction, arrangement and combination of elements described hereinafter and pointed out in the claims forming a part of this specification.

A practical embodiment of the invention is illustrated in the accompanying drawing, wherein:

Fig. 1 is a longitudinal sectional view of the trigger motor with the trigger in one inoperative position.

25 Figs. 2 and 3 are similar views with the trigger in other positions.

Fig. 4 is a view in side elevation of the trigger motor looking from the inside.

Fig. 5 is a detail view in rear elevation of the 30 trigger.

Fig. 6 is a sectional view on the line 6—6 of Fig. 3.

Referring to the drawing by characters of reference, there is shown a portion of a machine gun 35 including a breech casing having side walls 5—5 between which a breech bolt 6 is reciprocally mounted. The breech bolt is provided with the usual sear 7 which is adapted to be moved to releasing position by a sear slide 8.

40 The housing 9 of a trigger motor is attached to the side wall of the casing by means of screws 10—10. A guide member 11, retained in the front end of the housing by a nut 12 threaded to the housing, is formed with a non-circular chamber 13. A plunger within the housing consists of a bolt 14 having a non-circular head 15 slidably disposed in the chamber 13 and a nut 16 threaded on the bolt and having an enlarged head 17 with a milled rim 18.

An impulse transmitting cable 19 of the type shown in my prior Patent No. 1,770,125 of July 8, 1930, passes through the bolt 14 and is secured to the inner end thereof as by welding 20. The 55 outer portion of the cable is sheathed in a tube

21 which is inserted in a socket 22 in the outer part of the guide 11.

A spring 23 confined between the guide member 11 and the head 17 of the nut normally urges the plunger towards the rear of the housing. An 5 opening 24 is provided in the housing to give access to the nut and enable the nut to be turned to vary the length of the plunger and take up slack in the cable 19.

A bell-crank lever 25 disposed in a slot 26 in the rear end of the housing is mounted on a pivot pin 27 passing through its front outer corner and through the housing. A trigger 28 mounted on the rear corner of the lever by means of a pivot pin 29 is also disposed in the slot 26 in the housing and extends into an aperture 30 in the side wall 5 of the breech casing. The trigger is positioned so that it will strike the sear slide 8 when the trigger is moved inwardly towards the breech casing and when the breech bolt is in battery. A spring 31 anchored in the lever acts on the trigger to normally hold it against the rear face 32 of the aperture 30 and the rear face of the housing 9.

The lever 25 is connected to the nut 16 of the plunger by means of a link 33. The rear end 34 of the link is preferably inserted in the bifurcated inner corner of the lever and a pin 35 carried by the rear end of the link rides in aligned slots 36 in the bifurcated corner of the lever. 30 The shank of the link 33 extends through an aperture 37 in the head 17 of the nut and an enlarged head 38 on the front end of the link is disposed within the nut and bears against the inside face of the head 17 of the nut. The head 35 38 of the link and that portion extending through the aperture 37 are relatively rotatable with respect to the nut so that the nut may be turned on the bolt 14 to vary the length of the plunger and thereby take up slack in the cable 19. 40

With the parts in the position shown in Fig. 1, a pull on the cable 19 moves the plunger against the action of the spring 23. The plunger transmits this movement through the link 33 to the lever 25 which rotates about its pivot and moves 45 the trigger 28 through the aperture 30 in the side wall 5 where it strikes the sear slide 8 and causes release of the sear and firing of the gun. The parts are now in the position shown in Fig. 2. When the cable is released the spring 23 moves 50 the plunger rearwardly and restores the lever 25 to the position shown in Fig. 1.

As shown in Fig. 3 the pivotal mounting of the trigger is necessary because the trigger is reciprocated at a different frequency than the 55

normal rate of firing of the gun, and if it is in the inward firing position when the bolt of the gun is arriving in battery, the forward face of the sear slide 8 will strike the side of the trigger 5 and cause it to yield. Furthermore when firing is discontinued the impulse cable is held to maintain the plunger in the forward position thereby positioning the trigger in the path of the sear slide where it will be rotated by the sear slide as 10 the breech bolt arrives home after firing the last shot. The trigger will then be in safe or inoperative position until the cable is released to enable the lever 25 to assume the position as shown in Fig. 1.

15 I claim:

1. In a trigger motor, a housing, a guide in one end of the housing, a plunger in the housing comprising a bolt and a nut threaded thereon, the bolt slidably and non-rotatably mounted in the guide, a spring normally urging the plunger in one direction, a cable connected to the bolt and adapted to retract the plunger, a bell-crank lever pivotally mounted in the other end of the housing, a link having a relatively rotatable connection with the nut and a pivotal and sliding connection with the lever, a trigger pivotally carried by the lever, a spring carried by the lever and normally moving the trigger away from the lever, and means for limiting movement of the trigger under action of its spring.
2. In a trigger motor, a housing, a guide in one end of the housing, a plunger in the housing comprising a bolt and a nut threaded thereon, the bolt slidably and non-rotatably mounted in the guide, a spring normally urging the plunger in one direction, a cable connected to the bolt and adapted to retract the plunger, a bell-crank lever pivotally mounted in the other end of the housing, a link having a relatively rotatable connection with the nut and a pivotal and sliding connection with the lever, and a trigger pivotally carried by the lever.
3. In a trigger motor, a housing, a guide in one

end of the housing, a plunger in the housing comprising a bolt and a nut threaded thereon, the bolt slidably and non-rotatably mounted in the guide, a spring normally urging the plunger in one direction, means connected to the bolt and adapted to retract the plunger, a bell-crank lever pivotally mounted in the other end of the housing, a link connecting the nut and lever, and a trigger pivotally carried by the lever.

4. In a trigger motor, a housing, a guide in one end of the housing, a plunger in the housing comprising a bolt and a nut threaded thereon, the bolt slidably and non-rotatably mounted in the guide, a spring normally urging the plunger in one direction, means for retracting the plunger against the action of the spring, and a trigger movable by the plunger.

5. In a trigger motor, a housing, a plunger in the housing comprising a bolt and a nut threaded thereon, a spring normally urging the plunger in one direction, means for retracting the plunger against the action of the spring, and a trigger connected to the nut of the plunger and movable thereby.

6. In a trigger motor, a housing, a bell-crank lever pivotally mounted in the housing, a trigger pivotally carried by the lever, resilient means normally moving the trigger away from the lever, and a plunger having a pivotal and sliding connection with the lever.

7. In a trigger motor, a housing, a bell-crank lever pivotally mounted in the housing, a trigger pivotally carried by the lever, resilient means normally moving the trigger away from the lever, and means for rocking the lever.

8. In a trigger motor, a housing, a bell-crank lever pivotally mounted in the housing, a trigger carried by the lever, a plunger in the housing, and a link having a relatively rotatable connection with the plunger and a pivotal and sliding connection with the lever.

RICHARD C. COUPLAND.
